GUN RECOIL DAMPING STRUCTURE

Gervase M. Magrum and Frank M. Salisbury, Buffalo, N. Y.; said Magrum assignor to Houde Engineering Corporation, Buffalo, N. Y., a corporation of New York, and said Salisbury assignor to Bell Aircraft Corporation, Buffalo, N. Y., a corporation of New York

Application April 22, 1938, Serial No. 203,500

3 Claims. (Cl. 89—42)

This invention relates to the dampening or the absorption of the shock of recoil in guns, particularly guns of the machine or rapid fire type, such as guns mounted on airplanes.

In guns of the type referred to, the barrel structure is axially movable relative to the gun mounting, and the gunner grips the mounting adjacent to the breech end of the barrel structure for directioning and aiming of the barrel structure and for manipulation of the trigger mechanism for firing of the gun. When the gun is fired, the barrel structure recoils and moves back toward the operator, and unless such recoil movement is damped or absorbed, directioning, aiming and firing of the gun will be materially interfered with, with corresponding loss in accuracy as well as unnecessary discomfiture to the gunner and unnecessary strain on the gun.

An important object of our invention is to provide simple and efficient structure on the gun for dampening and absorbing the recoil shock, said structure being preferably of the hydraulic type.

A further object is to provide shock absorbing structure which can be readily applied to a gun without material increase of the gun size or bulk and which will not interfere with the balanced and efficient manipulation and firing of the gun.

The above and other features of our invention are incorporated in the structure disclosed on the accompanying drawing, in which drawing:

Figure 1 is a plan view, more or less diagrammatic, of a gun structure showing our improved shock absorbing means applied thereto;

Figure 2 is an enlarged section on plane II—II of Figure 1; and

Figure 3 is an enlarged section of the hydraulic fluid flow controlling valve structure.

Referring to Figure 1, the gun structure support may be in the form of a post or pedestal 10 having at its lower end a pin 11 for journaling in the socket of a suitable base (not shown) which may be stationarily mounted, as on an airplane or which base may have a tripod or other support so that the gun structure may be portable. The post or pedestal 10 may be U-shaped and between its side walls 12 and 13 the gun barrel body 14 is received and guided, the gun barrel 15 extending forwardly from said body.

At the breech end of the gun barrel structure is a cross-frame 16 supporting grips 17 and 17' and the trigger mechanism 18 between the grips. A projection from the breech end of the gun

5 barrel structure extends through a cap 19 secured to the frame 16.

At its end the frame 16 has socket extensions 20 and 20' for receiving the inner ends of tubes 21 and 21' respectively, these tubes extending forwardly parallel with the gun barrel structure. Secured on the tubes 21 and 21' are brackets 23 and 23' receiving trunnion pins 24 and 24' supported by and extending laterally from the walls 10 12 and 13 of the pedestal 10. The frame 16 and the tubing extending therefrom thus form a framework which may be swung in a vertical plane on the trunnion pivot and which can be swung in a lateral direction with the post 10 on the axis of the pivot pin 11.

In accordance with our invention we provide shock absorbing structures S and S' whose stationary or cylinder elements C are the outer ends of tubes 21 and 21' respectively and whose 20 piston elements P are connected to the forward end of the barrel structure body 14 so that this structure is vertically supported at its forward end, the barrel structure being thus axially shiftable under recoil but under control of the shock 25 absorber structure.

The details of construction of the shock absorber mechanism is shown in Figures 2 and 3. The outer ends of the tubes 21 and 21' are reamed to form the cylinder element C, and a plug 25 30 secured by a rivet 26 forms the inner cylinder head. In order to seal this end of the cylinder, a soft gasket 27 is tightly squeezed against the head by a washer 28 held by a screw 29.

Secured to the outer end of cylinder tube, as 35 by welding, is a flange 30 to which is detachably secured, as by screws 31, the outer head or body 32, the head end 32' extending a distance into the cylinder tube, the head 32 being thus rigidly secured to the cylinder tube co-axial therewith.

40 The head 32 has the inner bore 33 communicating with the space within the cylinder tube 21, and an outer bore 34 of less diameter. The piston rod 35 extends through these bores and in the bore 34 is a bearing bushing 36 of suitable 45 metal for the rod. The outer end of the body 32 is expanded to form a recess for suitable packing assembly 37 around the piston rod to prevent leakage. Secured to the outer end of the rod 35 is an eye 38, the gun barrel body structure 50 14 having laterally extending lugs 39 and 39' to which the outer ends of the piston rods of the shock absorber structures are connected as by screws extending through the apertures of the eyes 38.

At its inner end, each piston rod has a reduced

portion or neck 41 threaded for reception of a piston 42. The piston is screwed tightly against the shoulder 43 and the piston rod and is locked in place by the base 44 threading on the end of the neck 41 and supporting the valve housing 45. This valve housing is in the form of a cylindrical cup and may be formed integral with the base 44 and has a comparatively large fluid flow passageway 46 in its outer wall, and one or more passageways 47 in its side wall. At its inner end the piston rod 35 has the bore 48 extending through the neck 41 for communication with the space within the valve housing chamber. At its outer end, the bore 48 is connected by passages 49 with the cylinder space at the outer side of the piston. The connection of the bore 48 with the cylinder space at the inner side of the piston is controlled by a valve 50 which, as shown, is a thin metal disc having a metering orifice 51, a spring 52 within the valve housing tending to hold the valve disc seated against the inner end of the piston rod across the end of the bore 48.

Seating against the shoulder between the bores 33 and 34 of the head 32 is a washer 53 and on the piston rod is an annular flange or collar 54. A spring 55 within the cylinder wall 21 abuts the washer 28 and the base 44 of the valve housing, the spring being centered by the valve housing and by a boss or lug 56 on the washer 28. The spring forms part of the shock absorber action and tends to resist inward movement of the piston structure and to hold the piston structure in outer position with the flange or collar 54 in abutment with the washer 53.

Each shock absorber body structure 32 has a top extension 57 providing a filling and expansion chamber for hydraulic fluid, the chamber being closed by a cover 59. A filler screw 60 allows filling of the shock absorber working chambers and the reserve or filler chamber 58 to 40 the proper level, the chamber 58 being connected with the working chamber 33 by a passageway 61.

The space 33 and the space within the cylinder tube 21 forms the low pressure working space or chamber of the shock absorber while the space within the cylinder 21 at the inner end of the piston forms the high pressure working chamber.

When the gun is fired, it recoils, or in other words moves back toward the operator and, unless the recoil were checked or damped, accurate firing would be prevented. However, when the shock absorber structure is applied to the gun and the gun barrel structure recoils, the shock absorber piston structure will be shifted inwardly in the cylinder structure, and the spring 55 will be compressed and will resist and cushion such inward movement. At the same time, the fluid in the inner or high pressure working chamber of each shock absorber is displaced by the piston and the pressure against the valve disc 50 will keep the disc seated so that the displaced fluid can escape only through the restricted orifice 51 for flow through the piston bore 48 and passages 49 to the outer or low pressure working chamber 33, the resistance to flow through the orifices thus determining the hydraulic shock absorber resistance to recoil, this hydraulic resistance to flow in conjunction with the spring resistance determining the dampening or shock absorbing control by the shock absorber structure of the gun recoil movement. After dampening and dissipation of the recoil movement, the springs 55 function to shift the piston rod structures and, therefore the barrel structure moves 75

back into firing position, and during outward movement of the piston structure the suction created in the inner or high pressure working chambers will unseat the valve discs 50 for comparatively free flow from the low pressure working chambers to the high pressure working chambers. The increasing length of piston rod entering the low pressure chamber will create a volume differential between the working chamber but the excess fluid may flow into the chambers 58 to be returned to the working chambers during outward stroke of the piston structures so that both low and high pressure working chambers will be refilled with hydraulic fluid.

The valve discs may be very thin so that the orifices 51 would be of the sharp edge type so as to compensate for change in the viscosity of the hydraulic fluid and the hydraulic shock absorber resistance will remain uniform independently of viscosity variation. By providing shock absorbers at opposite sides of the gun barrel structure and parallel therewith, the shock absorber load is distributed and the operation of the gun is more balanced. With the arrangement shown, the shock absorber structure can be easily and readily moved from the gun for inspection, adjustment or repair, and with the shock absorbers applied as shown they will add very little to the bulk of the gun and will not interfere with the proper directioning, aiming, firing or other manipulations of the gun.

We have shown a practical and efficient embodiment and application of our invention but we do not desire to be limited to the exact construction, arrangement and operation shown and described as changes and modifications may be made without departing from the scope of the invention.

We claim as follows:

1. A gun structure comprising a barrel body having a gun barrel extending from the forward end thereof, means to support said body for tilting, said means comprising a U-shaped support, a frame comprising a pair of elongated tubes disposed extending one along each side of said body, respectively, and connected adjacent the breech end of said body by a crossmember connected with the breech end of said body, said tubes being each pivotally connected to a free arm of said U-shaped support and adjacent the forward end of said tubes, means connecting said frame with the forward end of said barrel body for controlled longitudinal movement of said body with respect to said frame, said means comprising pistons entered slidably in the forward end of said tubes, respectively, piston rods connected to said pistons and pivotally connected at their forward ends to the forward end of said body, each of said tubes being provided with a plug abutment member therein and secured thereto, and being provided with compression spring means disposed extending between said pistons and said plugs, housings defining an oil reservoir and also defining guides for said piston rods, said housings each comprising a tubular body having a reduced portion entered in the forward end of a tube and having an enlarged portion in abutting relation to the forward end of a tube, and means on said housing forming a sealed connection with a piston rod slidable therein.

2. In a gun structure which includes a frame comprising a pair of spaced elongated tubes and a gun barrel body disposed between said tubes, means connecting said frame and said barrel body for support of said body and for controlled

relative movement of said body and frame, said means including a pair of tubular housings, one for each of said elongated tubes, with each of said housings having a portion thereof entered in the forward end of a tube, a first flange on the forward end of each tube, respectively, a second flange on each of said housings, respectively, and removably secured to a first flange, each of said housings being provided with a piston rod slidable therein and extending therethrough, with each piston rod being pivotally connected at one end to the forward end of said barrel body and having a piston on its other end entered in said tube, and means in each of said tubes and in each of said housings arranged cooperable with said pistons to control relative movement of said barrel body and said frame.

3. In a gun structure which includes a frame comprising a pair of spaced elongated tubes and a gun barrel body disposed between said tubes, means connecting said frame and said barrel body for support of said body and for controlled

relative movement of said body and said frame, said means comprising a pair of tubular housings, one for each of said elongated tubes, with each of said housings having a portion thereof entered in the forward end of a tube, a first flange on the forward end of each tube, respectively, a second flange on each of said housings, respectively, and removably secured to a first flange, each of said housings being provided with a piston rod slidable therein and extending therethrough, with each piston rod being pivotally connected at one end to the forward end of said barrel body and having a piston on its other end entered in a said elongated tube, each of said housings being provided with a bored side boss arranged providing an oil reservoir in fluid communication with a said elongated tube to which the housing is connected, each of said piston rods carrying a valve housing entered in a said tube, and a valve in each of said valve housings, respectively.
